JOHN F. O'CONNOR, OF CHICAGO, ILLINOIS; ASSIGNEE TO WILLIAM H. MINER, OF CHAZY, NEW YORK.

DRAFT-RIGGING YOKE.

1,198,751.

Specification of Letters Patent. Patented Sept. 19, 1916.

Application filed November 30, 1914. Serial No. 874,691.

To all whom it may concern:

Be it known that I, JOHN F. O'Connor, a citizen of the United States, residing at Chicago, in the county of Cook and State 5 of Illinois, have invented a certain new and useful Improvement in Draft-Rigging Yokes, of which the following is a full, clear, concise, and exact description, reference being had to the accompanying drawings, forming 10 a part of this specification.

This invention relates to improvements in draft rigging yokes.

An object of the invention is to provide a two part yoke for railway draft riggings 15 which may be employed in connection with standard types of draw bars and detachably connected thereto by pins or bolts accommodated in the usual rivet holes provided in such draw bars.

20 In the drawing forming a part of this specification, Figure 1 is a side elevation of a portion of a draw bar and a yoke showing my improvements in connection therewith. Fig. 2 is a top plan view of the structure 25 illustrated in Fig. 1. Fig. 3 is a vertical sectional view taken on the line 3—3 of Fig. 1 and Fig. 4 is a horizontal sectional view through the forward ends of the two yoke parts to illustrate the construction thereof. 30 Figs. 5, 6, 7 and 8 are views corresponding respectively with Figs. 1, 2, 3 and 4, showing another embodiment of my invention.

In said drawing, and referring to Figs. 1 to 4 inclusive, 10 denotes an M. C. B. draw 35 bar, the butt 11 of which is provided with the usual upper and lower shoulders 12—12 and standard spaced rivet holes 13—13.

The improved yoke, which is designated generally by the reference A, comprises two 40 like parts 14 and 15, each of which has upper and lower arms 16—16, rear connecting piece 17, front side plate or wall 18 and upper and lower inwardly extending flanges 20 and 21, which flanges 20 and 21 engage 45 the upper and lower surfaces of the draw bar butt. The upper flange 20 of the member 15, as shown in Fig. 2, has an extension 22 which is perforated as indicated at 23 in alignment with the rivet hole 13. The upper flange 20 is also cut away as indicated at 50 24 to receive a corresponding extension on the member 14. The lower flange 21 of the member 15 is provided with a semi-circular extension 25 which is perforated as indicated at 55 26 in alignment with the front rivet

hole 13. The flange 21 is also recessed as indicated at 27, back of the extension 25 to receive the corresponding extension on the other member 14. As will be understood, the extension 22 on the upper flange 20 of the member 15 is directly above the recess 27 on the lower flange 21 thereof and conversely with regard to the recess 24 and extension 25. The members 14 and 15, being counterparts, when placed opposite each other will have the extensions 22 and 25 of the one fit in the corresponding recesses 24 and 27 of the other, which will therefore bring the perforations 23 and 26 on the upper and lower flanges in alignment with the rivet holes 13—13. When the yoke parts are thus assembled, they may be detachably secured to the draw bar by inserting headed pins 28—28, retained in place by cotters 29—29. At their front ends each 71 of the yoke members 14 and 15 is also provided with transversely extending shoulders 30—30 which coöperate with the shoulders 12 on the draw bar and at their rear ends the yoke members are provided with perforated ears 31 to receive a bolt 32 there-through, by which the rear ends of the yoke members may be securely held together.

In the structure shown in Figs. 5 to 8 inclusive, the yoke members 114 and 115 are 85 counterparts, each having a side wall 118, upper and lower flanges 120 and 121, said flanges having extensions 122 and 125, each extension being provided with two perforations 123 and 126, adapted to align with the 90 standardly spaced rivet holes in the draw bar 110. The upper flange extension 122 is beveled on its under side, as indicated at 40, and the lower extension 125 is beveled on its under side as indicated at 41. Consequently, when the two members 114 and 115, which are counterparts, are placed opposite each other, as clearly indicated in Fig. 7, the beveled extension 122 of the one member will snugly fit over the beveled extension 125 100 of the other member and when thus assembled, the perforations 123 and 126 are in alignment with the rivet holes and the yoke members may be detachably connected to the draw bar by a pair of pins 128—128 which, in this instance, I have shown as connected together by a single head 42. The yoke members 114 and 115 are also provided with shoulders 130 coöperable with the usual upper and lower shoulders on the draw bar. 105 110

- Although I have herein shown and described in detail two forms of my invention, I do not wish to be limited thereto, inasmuch as I am aware that my improvements 5 may be embodied in other structures than those herein disclosed and particularly do I wish to avoid being limited to a two part yoke of the vertical type, except in so far as necessitated by the claims appended hereto.
- 10 I claim:—
1. In a device of the character described, the combination with a draw bar having standardly spaced and located rivet holes therein, of a yoke comprising two separable members each having upper and lower flanges extended over the upper and lower 15 surfaces of the draw bar butt, portions of said flanges over-lying said rivet holes and being perforated in alinement therewith, and removable pins extending through said perforated portions and the rivet holes of 20 the draw bar.

JOHN F. O'CONNOR.
